2,118,206

FINNED TYPE COOLING UNIT

Richard W. Kritzer and Anthony F. Hoesel, Chicago, Ill., assignors to Peerless of America, Chicago, Ill., a corporation of Illinois

Application February 7, 1935, Serial No. 5,398

5 Claims. (Cl. 257—255)

The type of coils, to which the invention relates, are well known in the art, and generally designated as fin coils. These fin coils are comprised of the combination of a refrigerant conduit having parallel courses upon which are mounted, in thermal relationship, a multiplicity of fin surfaces for the purposes of increasing the effective heat transfer surface, and to facilitate the defrosting of the cooling unit during the stoppage of 5 the refrigerant circulation through the refrigerant conduit.

One object of our invention is to increase the thermal efficiency of fin coils, thereby enabling a smaller amount of material to effectuate the same 15 heat transfer, at given temperature differences, as would be obtained with a much greater amount of material fabricated and assembled in the usual compactly nested form.

Another object of our invention is to facilitate 20 the defrosting of fin coils, and especially so, the lowermost fins of a cooling unit comprised of a plurality of vertical fins.

In the drawing:

Figure 1 is an end elevational view partly in 25 section of a fin coil fabricated in accordance with our invention.

Figure 2 is a side elevational view of Figure 1.

Figure 3 is an isometric view of an end tie plate 30 means as embodied in the invention.

Figure 4 shows a spiral ribbon, which is placed inside the refrigerant conduits.

Referring to the drawing:

Figures 1 and 2 show a refrigerant conduit 5 formed of a single continuous tube bent into zig-zag form. A plurality of square fins 6 are spaced apart upon the straight portions or courses of the conduit, but no fins are placed upon the return bend portions 7. The fins are so located upon the courses that their diagonals are vertical and 40 horizontal. End plates 8 through which the return bends project, hold the several courses of the coil in proper spaced relation to each other.

The above form of construction is clearly outlined in the Anthony F. Hoesel applications, Serial 45 No. 591,086 filed February 5, 1932, which has since matured into Patent No. 1,988,494, dated January 22, 1935, and Serial No. 710,262 filed February 8, 1934, now Patent No. 2,065,586, issued Dec. 29, 1936 respectively, for the coil and a machine for 50 fabricating the same.

In Figure 3, the end plate 23 has slots 24 and holes 25 through which project the return bends and the end portions respectively of a cooling unit made in accordance with the above description of 55 Figures 1 and 2.

Figure 4 shows a spiral ribbon 26, which has a pitch 27. The outside diameter 28 is somewhat larger than that of the internal diameter of a refrigerant conduit into which the spiral ribbon 26 is introduced by means of passing a bar 5 through the inside bore of the refrigerant conduit prior to the bending of the return bends. The end of the spiral ribbon is attached to the aforesaid bar which by being rotated in the proper direction also rotates the spiral ribbon in the 10 proper direction, so that while the frictional engagement of the outside diameter of the spiral ribbon with the inside diameter of the refrigerant conduit produces a frictional drag, the spiral ribbon in turn, due to its proper rotations, tends 15 to increase its pitch and consequently decrease its outside diameter. These two tendencies automatically balance themselves so that whenever the spiral ribbon is rotatively pulled through the refrigerant conduit, it is in tight engagement with 20 the internal walls of the refrigerant conduit. The purpose of the spiral ribbon is to convert the normal passage velocity, of a refrigerant inside a conduit, into that of a rotary motion, whereby the liquid is thrown into engagement with the 25 internal walls of the conduit, rather than flowing in the bottom portion only of the conduit. This increase of wetted wall surface results in an acceleration of the vaporization of the liquid and consequently a greater heat absorption for a given 30 length of conduit. The functions of this spiral ribbon 26, and other alternatives producing the same result, namely the rotation of the refrigerant within the conduit, are more fully disclosed in the Richard W. Kritzer and Anthony F. Hoesel 35 application, Serial Number 758,065 filed December 18, 1934.

In all convection circulation type cooling units, the warm air enters at the top and sides, and the cold air drops from the bottom, due to cooling 40 of the air producing decreased volume and consequently greater weight of the air per unit volume.

By means of placing fins upon a refrigerant conduit in the manner described above, we have 45 found that more air will pass through the cooling unit. This tends to resolve itself into greater convection air circulation at an increased temperature after passing through our coils as compared with a lesser convection air circulation at 50 a lower temperature after passing through other types of coils not employing our invention. While the air issuing from our coil is of a somewhat higher temperature, than that of the convection circulated air of other type of coils, the increased 55

quantity of convection circulation provides a net gain in the amount of heat transferred from the air to the cooling coil.

The above relates to cooling coils of the form disclosed in the drawing but without having the spiral ribbon inserted within the refrigerant conduit. After inserting the spiral ribbon we then find that the efficiency of the cooling coil is materially increased and the increased convection air circulation is maintained, and in many cases increased, and the temperature of the air, after passing through the cooling coil, is materially decreased, which results in getting a greater heat transfer from a given amount of material comprising the cooling coil as compared to the heat transfer of an equivalent amount of material fabricated into other types of coils.

We have further found that positioning the fins as shown in the drawing results in a ready defrosting of the cooling coil, since at least some of the corners of all the fins are subject to circulation of air, which is only partly cooled, whereas the close nesting of the fins, as generally employed, results in a delayed defrosting, which, in an automatic refrigerating system, would prove objectionable.

We claim:

1. In a cooling unit, the combination of parallel spaced apart refrigerant conduit courses, a multiplicity of substantially rectangular and spaced apart fins mounted upon and individual to a single course, the diagonal lines of the fins being in substantially vertical and horizontal planes, and end means to maintain the spaced apart relationship of the conduit courses.
2. In a cooling unit, the combination of parallel spaced apart refrigerant conduit courses, a multiplicity of substantially rectangular and spaced apart fins mounted upon and individual to a single course, the diagonal lines of the fins being in substantially vertical and horizontal planes, and end means to maintain the spaced apart relationship of the conduit courses, the said

end means comprising a plate with slots, through which project the return bends joining adjacent courses of the refrigerant conduit.

3. In a cooling unit, the combination of parallel spaced apart refrigerant conduit courses, a multiplicity of substantially rectangular and spaced apart fins mounted upon and individual to a single course, the diagonal lines of the fins being in substantially vertical and horizontal planes, and the refrigerant conduit having a spirally wound member inserted therein to provide a helical path adjacent the internal wall of the refrigerant conduit.

4. In a cooling unit, the combination of parallel spaced apart refrigerant conduit courses, a multiplicity of substantially rectangular and spaced apart fins mounted upon and individual to a single course, the diagonal lines of the fins being in substantially vertical and horizontal planes, and end means to maintain the spaced apart relationship of the conduit courses, and the refrigerant conduit having a spirally wound member inserted therein to provide a helical path adjacent the internal wall of the refrigerant conduit.

5. In a cooling unit, the combination of parallel spaced apart refrigerant conduit courses, a multiplicity of substantially rectangular and spaced apart fins mounted upon and individual to a single course, the diagonal lines of the fins being in substantially vertical and horizontal planes, and end means to maintain the spaced apart relationship of the conduit courses, the said end means comprising a plate with slots, through which project the return bends joining adjacent courses of the refrigerant conduit, and the refrigerant conduit having a spirally wound member inserted therein to provide a helical path adjacent the internal wall of the refrigerant conduit.

RICHARD W. KRITZER.
ANTHONY F. HOESEL.
